RABBIT FIGURE ON A LOG TOY

Charles K. Grieder, 700 S. Lyon,
Santa Ana, Calif. 92701

Filed Sept. 25, 1972, Ser. No. 292,235

Term of patent 14 years

Int. Cl. D21—01

U.S. Cl. D34—15 B

FIG. 1

FIG. 5

FIG. 1 is a side elevational view of a rabbit figure on a log toy showing my present design, the opposite side being a mirror image thereof;

FIG. 2 is a top plan view of such toy;

FIG. 3 is a bottom plan view thereof;

FIG. 4 is a front elevational view of the toy; and

FIG. 5 is a rear elevational view of the toy showing my present design.

I claim:

The ornamental design for a rabbit figure on a log toy, substantially as shown and described.
